UNITED STATES PATENT OFFICE

CLARA SAFFOLD, OF LOS ANGELES, CALIFORNIA

DESIGN FOR A SMOKER'S STAND

Application filed May 1, 1931. Serial No. 39,678. Term of patent 7 years.

To all whom it may concern:

Be it known that I, CLARA SAFFOLD, a citizen of the United States of America, residing at Los Angeles, in the county of Los Angeles and State of California, have invented a new, original, and ornamental Design for a Smoker's Stand, of which the following is a specification, reference being had to the accompanying drawings, forming a part thereof.

Fig. 1 is a front elevation of my new design,
Fig. 2 is a side elevation of my new design,
and

Fig. 3 is a top plan view of the cap disclosing the concave formation of the same.

I claim:—

The ornamental design for a smoker's stand substantially as shown.

CLARA SAFFOLD.
